E. A. RYDER

DUPLEX DRIVING MECHANISM

Filed Feb. 28, 1923

UNITED STATES PATENT OFFICE.

EARLE A. RYDER, OF KEYPORT, NEW JERSEY, ASSIGNOR TO AEROMARINE PLANE & MOTOR COMPANY, A CORPORATION OF NEW YORK.

DUPLEX DRIVING MECHANISM.

Application filed February 28, 1923. Serial No. 621,815.

To all whom it may concern:

Be it known that I, EARLE A. RYDER, a citizen of the United States, and a resident of Keyport, in the county of Monmouth and State of New Jersey, have invented certain new and useful Improvements in Duplex Driving Mechanism, of which the following is a specification, reference being had to the accompanying drawings, forming part of this specification.

This invention relates in general to an improved form of driving mechanism for accessories such as are usually associated with an internal combustion engine, and applies more specifically to aircraft engines although not confined thereto. It specially aims at an improved manner in which an engine-driven accessory such as a fuel pump may be operated manually or from another source such as a starting motor when the engine is at rest just prior to its being started.

The present embodiment and its specific application as herewith illustrated characterizes a driving mechanism having novel and improved features in which the mechanism is so constituted as to provide a simple means in a most compact form for manually or otherwise operating an engine-driven fuel pump when it is desirable to supply a small amount of fuel to the engine for starting purposes, the driving elements featured in this invention being so formed and so disposed relatively to one another as to automatically mesh or demesh when one or the other of the driving means is functioning, thus insuring against fracture or jamming of the parts, as will be more fully described hereinafter.

Another feature of this invention is the construction and its mode of operation so as to permit of the manual or other driving means being placed in a position remote from that of the pump or in an accessible or convenient location and the pump operated thereby without resorting to a complex mechanism of intermediate gears or other driving means.

A further feature of this invention consists in providing a device in which the construction is such as to avoid constantly contacting latches or ratchets which are noisy and subject to much wear, in the present construction the engaging elements are such as to permit of them being entirely free of one

another when moved to a disengaged position.

The pump as herein shown is of a conventional type well known to those skilled in the art, and is not in itself a feature of this invention, furthermore, it is to be understood that the driving mechanism disclosed in this instance is not confined to the operation of a fuel pump exclusively, it being obvious that the same is applicable with slight modification to other devices not shown or described herein.

A suitable mechanism is herein provided for an engine-driven accessory in which the accessory may be driven manually or otherwise at a point remote therefrom, as by flexible driving connection and in which the automatic meshing of said manual or alternative driving means with the driven means may be accomplished by the rotation of the driving means, said meshing and demeshing features being so constituted that the two distinct driving means cannot coact to simultaneously drive the accessory associated therewith.

Various other objects and advantages of the invention will be in part obvious from an inspection of the accompanying drawings and in part will be more fully set forth in the following particular description of one form of mechanism embodying my invention, and the invention also consists in certain new and novel features of construction and combination.

In the drawings:—

Figure 1 is a vertical longitudinal section of the invention taken approximately in the center.

Figure 2 is a fragmentary sectional view similar to Fig. 1 showing the elements in another position.

In the present instance 10 designates a housing which is attached to an engine in any suitable manner and in which the principal parts of the mechanism are contained. A gear 11 is driven by the engine and in turn drives a gear 12 having angular clutch teeth 13 on the side thereof, said gear being mounted for free rotation upon a shaft 14 and adjacent to a shoulder 15 on said shaft. To the shaft 14 there is secured a sleeve member 16 having angular clutch teeth 17, 18, said sleeve being rotatably supported in a relatively large bearing 19,

The gear 12 is disposed between the shoulder 15 and the clutch teeth 17 so as to permit of it having an axial movement therebetween. Secured to the shaft 14 is a spur 5 gear 20 meshing with one or more similar gears (not shown) which constitutes the fuel pumping means, said fuel being drawn through an inlet tube 23 and expelled through the outlet tube 24 due to the rotation of said 10 gears in a manner well understood.

In a cylindrical extension 26 there is disposed an auxiliary shaft 27, axially aligned with the shaft 14 and having an enlarged end portion 28. Upon the portion 28 there 15 is mounted in a manner so as to be slidable thereon, a sleeve member 29 having angular clutch teeth 31 adjacent to the clutch teeth 18 and adapted to engage the same. One or more (as may be found convenient) angular 20 slots 32 are formed in the sleeve, said slots coacting with one or more pins 33 secured in the enlarged end portion 28, the ends of said pins projecting outward in a manner so as to engage in the slots 32.

25 To the shaft 27 there is secured in any suitable manner a flexible shaft 34 said flexible shaft being connected to a gear drive 35, 36 contained in a housing 37 and operated in this instance by a hand crank 38. 30 The housing 37 may be secured to the engine as by screws 39 in any convenient and accessible location from the main portion of the mechanism.

In operation, and assuming the elements 35 in the positions occupied while the engine is at rest as shown in Fig. 1; when it is desired to supply a quantity of fuel to the engine for starting purposes, the hand crank 38 or alternative driving means is rotated in 40 a clock-wise direction thereby operating the gear drive 35, 36 which in turn drives the flexible shaft 34 connected to the shaft 27 and which is thereby likewise rotated; as the shaft 27 starts to rotate, the sleeve 29 will 45 be moved axially into mesh with the sleeve 16 due to the angular slots 32 and the action of the pins 33 thereagainst, to a position as shown in Fig. 2. The initial axial movement having been completed, the sleeves 16 50 and 29 and the shaft 14 will be caused to rotate and the pump operated; said rotation will effect a demeshing action of the clutch teeth 13 and 17 due to the angularity of the same and slide the gear 12 over against the 55 shoulder 15 where it will not obstruct the rotation of the shaft 14.

It is obvious that the alternative driving means such as a hand crank or other power device can be connected directly to the end 60 of the shaft 27 and adjacent to the mechanism when it is so desired.

With reference to Fig. 1, when the engine has started up under its own power the frictional contact of the gear 11 against the gear 65 12 (direction of rotation as indicated by the

arrows) will be sufficient to force the gear 12 again into mesh with the sleeve 16 and also cause a demeshing of the clutch teeth 18, 31 due to their formation as will be readily understood from the drawings.

70

In the above described manner the pump can be operated either from the engine drive shaft or from an alternative source provided for this purpose.

It is to be noted that when either the 75 gear 12 or the sleeve member 29 is moved to a disengaged position, they are entirely free of the intermediate sleeve member 16, thus providing a quiet running mechanism in which clattering and fast wearing ratchets 80 and latches have been avoided.

Variations may be resorted to within the scope of the invention and portions of the improvements may be used without the others whilst not departing from the spirit 85 of the invention.

Having thus described my invention, I claim:—

1. An engine accessory driving mechanism comprising an accessory drive shaft, a plurality of driving means adapted to individually operate the shaft, a fixed member on the shaft, and means axially slidable on the shaft into engagement with the fixed member, said fixed member so constituted 90 that only one of said driving means can operate the shaft at any one time.

2. In the art of driving a device from any one of several sources of power, a shaft to be driven, a plurality of slidable members 100 each driven from one of said sources of power, a fixed member on the shaft adapted to be engaged by any one of said slidable members one at a time.

3. A device of the character described, 105 comprising, a shaft to be driven, a plurality of driving means adapted to operate said shaft, a member fixed on the shaft and adapted to be engaged on either side by one of said driving means to drive the same, 110 said member so constituted as to be engaged by the one of said driving means having rotational speed in excess of the others.

4. In a driving mechanism for an engine 115 accessory, a shaft to be driven from the engine to operate said accessory, an alternative driving means therefor, means comprising members on the shaft adapted by being axially slidable thereon to automatically effect a disengagement of one 120 of said driving means when the other of said driving means is operating the shaft.

5. A driving mechanism for an engine accessory, comprising, a shaft to be driven from the engine to operate said accessory, 125 an alternative driving means located at a point remote from the accessory and adapted to drive the same when the engine is at rest, a fixed member on the shaft having two engaging faces and adapted to be engaged in 130

a manner as to be driven from either the engine or the alternative driving means.

6. In an engine accessory driving mechanism, the combination of a plurality of driving means, a device to be driven, a driving connection therefor adapted to be engaged by any one of said driving means to operate the same, one of said driving means adapted to permit of it being located at a point remote from said device, and separable clutch means axially slidable for automatically disengaging the other of said driving means when the rotational speed of one of said means exceeds the other.

15 7. In a device of the class described, a plurality of driving means, a device to be driven thereby, one of said driving means being located at a point remote from the other of said means, a flexible driving connection associated therewith to drive the device, and means comprising an axially slid- 20 able and separable connection adapted to automatically disengage the other of said driving means when one of said means is 25 functioning.

8. In an internal combustion engine, the combination of a device to be driven thereby, an auxiliary driving means therefor to be operated when the engine is at rest, a drive shaft for said device, an axially shiftable gear on the drive shaft driven from the engine and adapted to engage the shaft to rotate the same, means adapted to engage the shaft to rotate the same from the auxiliary driving means when the engine is at rest, said means so constituted as to effect a disengagement of the shiftable gear when so operated, and further adapted to disengage the auxiliary driving means when the 40 engine is functioning.

9. A driving mechanism comprising a device to be driven, a drive shaft therefor, a shiftable gear thereon having means adapted to engage the shaft to drive the same, a first driving means, a second driving means, the first of said driving means associated with the shiftable gear and adapted to effect an engagement thereof with the drive shaft, a shiftable member associated with the second 45 said driving means and adapted to engage the shaft to drive the same, and means so constituted as to effect a disengagement of either one of said driving means when the rotational speed of one exceeds the other.

55 10. In a device of the class described, the combination of an engine having a drive shaft with a gear thereon, an accessory adapted to be attached to the engine, a drive shaft for said accessory, a fixed member on the drive shaft, an auxiliary shaft axially aligned with the accessory drive shaft, an axially shiftable gear mounted for free rotation on the drive shaft, said gear driven by the first gear and having means on the 60 side thereof adapted to engage said fixed

member on the shaft to drive the same when the engine is operating, a subordinate driving means located at a point remote from said accessory, a flexible driving connection between said driving means and the accessory, said flexible connection attached to the auxiliary shaft, a shiftable member associated with the auxiliary shaft said member having means adapted to engage said fixed member on the drive shaft in a manner 75 so as to rotate the same and other means so constituted as to permit of the accessory being driven by that one of said means whose rotational speed is predominant.

11. In a device of the class described, the combination of an engine having a drive shaft with a gear thereon, an accessory adapted to be attached to the engine, a drive shaft for said accessory, a fixed member on the accessory shaft, an auxiliary shaft co- 80 axial with the accessory shaft, an axially shiftable gear mounted for free rotation on the drive shaft, said gear driven by the first gear and having means on the side thereof 85 adapted to engage the fixed member on the shaft to drive the same when the engine is operating, a subordinate driving means located adjacent to said accessory and attached to said auxiliary shaft, a shiftable member associated with the auxiliary shaft, 90 said member having means adapted to engage said fixed member on the drive shaft in a manner so as to rotate the same and other means so constituted as to permit of the accessory being driven by that one of said 95 means whose rotational speed is predominant.

12. A device of the character described comprising a driving means, a second driving means, a driven means, a main drive shaft for the driven means, an auxiliary shaft axially aligned therewith, a member on the auxiliary shaft adapted to be automatically advanced so as to engage the main shaft when the first said driving means is 105 functioning, a gear mounted for free rotation on the main shaft and associated with the second said driving means, means on the gear adapted to engage the main shaft to drive the same when the second said driving means is functioning.

13. In apparatus of the class described, a plurality of driving means, a driven means, a drive shaft for said driven means, a fixed means on the drive shaft to be connected to any one of said driving means to drive the same, shiftable means associated with the drive shaft adapted to axially slide into operative or inoperative positions with said fixed means in a manner so that said drive shaft can be operated by only one of said driving means at one time.

14. In an accessory for an internal combustion engine, a drive shaft for said accessory an axially shiftable gear on the shaft 120

- and operated by the engine, said gear adapted to be shifted so as to engage the shaft in a drivable manner when the engine is started, an auxiliary driving means for the 5 accessory, when the engine is at rest, means automatically operative to engage the shaft in a drivable manner by the auxiliary driving means, said means also adapted to effect a disengagement of the gear from the shaft.
- 10 15. A device alternatively operable from several sources of power comprising a drive shaft having engaging means thereon, a pair of members individually drivable and axially slidable on the shaft by a source of power 15 and adapted to nonconcomitantly engage the same.
- 16 A device for operating an engine accessory from either one of two sources of power comprising a shaft drivably connected to an 20 accessory, a driving connection including a pair of members axially slidable on the shaft, clutch means on the shaft adapted to be engaged by one of the slidable members having a driving connection with the engine, 25 said clutch means also adapted to be engaged by the other slidable member operated by a driving means other than said engine, said clutch means so constituted as to release by axial movement one of said members when 30 the rotational speed thereof is less than the other.
17. A power transmitting device adapted to transmit power from either one of two sources comprising a means to be driven, a 35 shaft to drive the same, means on the shaft adapted to be engaged by an axially shiftable member having a driving connection with a prime mover, said means also adapted to be engaged by an axially shiftable 40 member operable by a force other than said prime mover, said means so constituted as to release by axial movement one of said members when the rotational speed thereof becomes less than the other.
- 45 18. In apparatus of the class described, the combination of a means to be driven, a plurality of driving means, a shaft to be driven from said means, a fixed member on the shaft, engaging means on said member, 50 a gear axially shiftable on the shaft and adapted to engage the fixed member, said gear operated from one of said driving means and adapted to be shifted into engagement when so operated, an auxiliary shaft axially aligned with the aforesaid shaft and operated from one of said driving means, a slidable member on the auxiliary shaft, engaging means on the slidable member adapted to engage the fixed member, means on the auxiliary shaft adapted to 55 advance the slidable member to engage the fixed member when the shaft is operated, said engaging means on the shiftable gear and the slidable member so constituted as to 60 become effective only when the rotational speed of the driving means associated therewith is in excess of the other.
19. In a device of the class described, the combination of a housing, a drive shaft rotatably supported in the housing, clutch members on the shaft, a plurality of driving means to drive the shaft, a gear associated with one of said driving means and axially shiftable on the shaft thereby, clutch members on the gear adapted to engage the drive shaft when said gear is shifted by the driving means, an auxiliary shaft operated by another of said driving means, a shiftable clutch member on the auxiliary shaft adapted when rotated to engage the drive shaft, all of said members so constituted as to effect a release of the drive shaft from any of said driving means and to maintain a driving relation only with the driving means that excels in rotational speed.
20. The combination with an engine and a fuel pump driven from said engine, of a fuel pump drive shaft, a clutch member secured to the shaft, an engine driven gear having a clutch face and axially shiftable on the shaft into engagement with the clutch member when the engine is operating, an auxiliary shaft adapted to be manually driven, a member having a clutch face and axially shiftable on the auxiliary shaft so as to engage with or disengage from the clutch member, automatic means responsive to the manual driving means to effect the shifting of both the gear and said shiftable member when the engine is at rest in a manner so that said fuel pump shaft can be manually operated.
21. The combination with an engine and a fuel pump driven from said engine, of a fuel pump drive shaft, a gear axially shiftable on the shaft and driven from the engine, clutch means on the gear, a double faced clutch member on the shaft, said gear adapted to drivably engage one of the clutch faces when the engine is operating, an auxiliary shaft axially aligned with the fuel pump drive shaft and adapted to be manually driven, a member rotatable with and axially shiftable on the auxiliary shaft, said member adapted to drivably engage the other of said clutch faces when axially shifted, a means to shift said member when the shaft is operated said means comprising one or more angular slots in the member and pins in the auxiliary shaft to engage the slots, said clutch member so constituted as to release the fuel pump shaft from either one of said driving means and to be engaged and driven only by the one having the higher rotational speed.
22. The combination with an engine and an accessory driven from said engine, of an accessory drive shaft, a gear axially shiftable on the shaft and driven from the

engine, clutch means on the gear, a double faced clutch member on the shaft, said gear adapted to engage one of the clutch faces when the engine is operating, an auxiliary 5 shaft axially aligned with the accessory drive shaft and adapted to be driven from a source of power other than said engine, a member rotatable with and axially shiftable on the auxiliary shaft, said member 10 adapted to engage the other of said clutch faces when axially shifted, a means to shift said member when said power is operated and comprising one or more angular slots in the member and pins in the auxiliary 15 shaft to engage the slots, said clutch member so constituted as to release the accessory

shaft from either one of said driving means and to be engaged and driven only by the one having the higher rotational speed.

23. In a device adapted to operate a 20 driven means from either one of two driving means, an automatic axially slidable driving connection between said driving and driven means including an intermediate 25 non-slidable member adapted to maintain a driving relation with only one of said driving means at a time.

Signed at Keyport in the county of Monmouth and State of New Jersey this 23rd day of February A. D. 1923.

EARLE A. RYDER.
